UNITED STATES PATENT OFFICE.

JOHN K. CHACE, OF NEW YORK, N. Y., ASSIGNOR TO J. LUTHER BRIGHT,
OF SAME PLACE.

MACHINE FOR SCOURING SHEET METAL.

SPECIFICATION forming part of Letters Patent No. 359,919, dated March 22, 1887.

Application filed May 26, 1886. Serial No. 203,320. (No model.)

To all whom it may concern:

Be it known that I, JOHN K. CHACE, a citizen of the United States, residing at New York, in the county and State of New York, have 5 invented a new and useful Machine for Scouring Sheet Metal, of which the following is a specification, reference being had to the accompanying drawings, in which—

Figure 1 represents a partial plan view and 10 partial horizontal section of a scouring-machine embodying my invention. Fig. 2 represents a central cross section thereof on line xx , Fig. 1. Fig. 3 represents a partial side view and partial vertical longitudinal section 15 of a detached portion thereof. Fig. 4 represents an inverted plan view thereof.

Similar letters indicate similar parts.

The object of my invention is to produce a 20 simple and effective machine for scouring or polishing both surfaces of sheet-metal plates, and especially tinned sheet-iron obtained from waste material—such as tin cans or boxes—as more particularly described in a separate application for Letters Patent bearing even date 25 herewith and Serial No. 203,326.

The essential feature of my invention consists of two rotary scouring-disks, the faces of 30 which are opposite to each other, in combination with hollow shafts for the passage of sand or other scouring material to said faces of the disks and feed-rollers for the passage of the sheet-metal plates to and from the disks.

It also consists of a novel construction of the 35 scouring-disks, as hereinafter set forth, and of a novel means for conveying the sand or other substance to the surfaces of the disks, as hereinafter fully described.

Referring to the drawings, the letter A designates the bed of the machine, supporting 40 standards B B, which form the bearings for two independent shafts, C C, the axes of which substantially coincide with each other. On the inner ends of the shafts C C are mounted the scouring-disks D D, with their inner or 45 exposed faces opposite and contiguous to each other, so that a sheet-metal plate passing between the disks is exposed to the action of both disks, one on each side or surface thereof.

Each of the disk-shafts C C is provided with 50 a pulley, L, whereby it may be connected with

asuitable driving medium for imparting thereto and to the disks a rotary motion, which may be in one and the same or in opposite directions, due to the independent condition of the shafts, and in order to permit of compensating 55 for a wear of the disks either or both shafts may be provided with a grooved wheel, X, to engage with a shifting-lever, Y, having a set-screw, Z, for securing it in the desired position. Said disk-shafts C C are hollow, and 60 through each shaft extends a tube, E, the inner end or terminal of which is open and adjacent to the face of the respective disks, so that if these tubes are supplied with a scouring material—such as sand or emery—at the 65 outer end, this material is conveyed to the faces of the disks by means of the tubes.

In order to insure a uniform distribution of the sand or other material over the faces of the disks, the latter are provided with radial slots 70 or grooves F and with a central recess, G, communicating with said grooves as well as with the inner end of the conveyer-tubes E, so that the scouring material discharging from the tubes is received in said recess, and thence thrown 75 outward into and through the grooves by centrifugal force. The radial grooves F are preferably made to terminate within the outer edges of the disks D, as shown in Fig. 2, to prevent the escape of the securing material at 80 that point, and thus obviate waste. The conveyer-tubes E are inclined to the axes of the hollow shafts in an inward direction, as shown in Fig. 1, to facilitate the passage of the scouring material through them, and the inner ends 85 of the tubes being thus rendered eccentric to the disks, the said centrifugal force by which the sand is thrown into the grooves F of the disks is increased. Each of the conveyer-tubes E is provided at the outer end with a cap, 90 H, through which passes freely a nozzle, I, which is connected to a hopper, J, by means of a flexible tube, K, so that the conveyer-tubes may be continuously supplied with the desired scouring material from the hopper through 95 said nozzle.

The letters Q Q designate feed-rollers, which are arranged in pairs on opposite sides of the axes of the scouring-disks D D, said rollers, like the disks, being in vertical positions and 100

the points of contact thereof being substantially in the line of the space between the faces of the disks, so that if the proper motion is imparted to said rollers the sheet-metal plates 5 may be passed both to and from the disks by that means, the plates resting on bridges *m* of the bed.

Each pair of feed-rollers *Q* *Q* is geared together by means of pinions *R* *R*, Figs. 2 and 4, 10 and on the shaft of one of each pair of said rollers is mounted a pulley, *S*, which is connected with a pulley, *T*, Fig. 1, on one of the disk-shafts *C* *C*, by means of a band, *U*, passing also over intermediate guide-pulleys, *V* *V*, 15 so that a proper revolving motion is imparted to one of each pair of feed-rollers from said disk-shaft, whence such motion is transmitted to the other feed-roller by means of said pinions.

20 Each of the scouring-disks is composed of a spirally-wound strip of leather or other similar material, which is inclosed in a casing, *N*, and which, together with said casing, is secured to a head, *O*, of the proper disk-shaft 25 by means of screw-bolts *P*, the heads of which are flat and are fitted into the radial grooves *F* of the disks, the same abutting against the bottoms of said grooves when the bolts are tightened. By this construction one of the 30 edges of the strip is brought upon the faces of the respective disks to form the scouring-surface, and, due to the spiral arrangement of the band as well as the nature of the material thereof, a very effective action is thereby produced. The coils of said spirally-wound strip 35 composing the disks may be connected together, as by means of glue, to which may be added sand or the like to produce a permanent rough surface, and also oil to preserve a 40 soft condition of the leather.

What I claim as new, and desire to secure by Letters Patent, is—

1. In a machine for scouring sheet metal,

the bed *A*, having bridges *m*, in combination with guide-rollers *Q* and means, substantially 45 as described, for rotating said rollers, the independent shafts *C* *C*, having coinciding axes, and the scouring-disks *D* on the ends of said shafts, all substantially as and for the purpose set forth.

2. In a machine for scouring sheet metal, the bed *A*, having bridges *m*, in combination with the independent shafts, means, substantially as described, for adjusting one of said shafts so as to compensate for wear of the disk, and having disks *D* secured thereto, all substantially 50 as and for the purpose set forth.

3. In a machine for scouring sheet metal, the bed *A*, the independent hollow shafts *C* *C*, tube *E* in one of said shafts, and the disk *D*, with 55 central recess, *G*, and radial grooves *F*, the latter terminating within the disk, all of said parts being combined and arranged substantially as and for the purpose set forth.

4. In a machine for scouring sheet metal, 60 the bed *A*, with standards *B*, in combination with the independent shaft *C*, with disk *D* thereon, the grooved wheel *X*, mounted on said shaft, the pivoted shifting-lever *Y*, having one end thereof resting in groove of said 65 wheel *X*, and the clamping device *Z*, adapted to secure the other end of the said lever *Y* to the bed *A*, substantially as described.

5. In a machine for scouring sheet metal, 70 the disk *D*, formed of a casing, *N*, with a spiral strip of leather having a central recess and radial grooves, the latter terminating within 75 the outer edge of the disk, substantially as described.

Signed at New York, in the county and 80 State of New York, this 24th day of April, 1886.

JOHN K. CHACE.
